US0D1060050S

(12) **United States Design Patent** (10) **Patent No.:** **US D1,060,050 S**
(45) **Date of Patent:** **** Feb. 4, 2025**

(54) **TRAY COVER**

(71) Applicant: **Graphic Packaging International, LLC**, Atlanta, GA (US)

(72) Inventor: **Robert Ackroyd**, Leeds (GB)

(73) Assignee: **Graphic Packaging International, LLC**, Atlanta, GA (US)

(**) Term: **15 Years**

(21) Appl. No.: **29/821,528**

(22) Filed: **Dec. 30, 2021**

(51) LOC (15) Cl. **09-03**

(52) U.S. Cl.

USPC **D9/433; D9/416**

(58) **Field of Classification Search**

USPC D9/416, 721, 737-747, 751, 752, 755,
D9/756, 760, 761, 433, 435, 438, 443,
D9/455, 456
CPC .. B65D 71/50; B65D 71/125; B65D 71/0077;
B65D 71/0085; B65D 5/54; B65D 5/62;

Assistant Examiner — Katherine E Morris

(74) Attorney, Agent, or Firm — Womble Bond Dickinson (US) LLP

(57) **CLAIM**

The ornamental design for a tray cover, as shown and described.

DESCRIPTION

FIG. 1 is a perspective view of a tray cover showing my new design.

FIG. 2 is a left elevation view of the tray cover of FIG. 1.

FIG. 3 is a right elevation view of the tray cover of FIG. 1.

FIG. 4 is a front elevation view of the tray cover of FIG. 1.

FIG. 5 is a rear elevation view of the tray cover of FIG. 1.

FIG. 6 is a top plan view of the tray cover of FIG. 1.

FIG. 7 is a bottom plan view of the tray cover of FIG. 1; and, FIG. 8 is a plan view of the tray cover of FIG. 1 shown in an unfolded configuration.

The broken lines in the drawings depict portions of the tray cover that form no part of the claimed design.

1 Claim, 8 Drawing Sheets
